UNITED STATES PATENT OFFICE.

HARRY J. MOYER, OF CHICAGO, ILLINOIS.

CONVEYER CONTROL FOR JIGS.

Application filed October 31, 1922. Serial No. 598,128.

My invention relates to the handling of the slate discharge from jigs for the separation of coal and slate in the presence of water and may be applied to jigs of the type 5 having a movable section of the bottom, the position of which is controlled by the depth of slate in the jigger box and which controls the extent to which the slate gate is open, as covered by my Patents #1,225,157, #1,225,- 10 158, and #1,225,159.

The purpose of my invention is to do away with an adverse influence of the operation of the slate conveyer upon the discharge through the slate gate—that of causing more or less coal to escape with the slate.

A further purpose is to have the quantity of slate present in the jigger box control the operation of the slate conveyer.

20 A further purpose is to have the slate conveyer operate only during such time as there is an ample depth of slate in the jigger box.

25 A further purpose is to have the depth of the slate in the jigger box control the operation of the slate conveyer by closing an electric circuit controlling the operation of the slate conveyer when there is ample depth of the slate in the jigger box and of breaking this circuit so soon as there is no longer ample depth of slate in the jigger box.

30 A further purpose is to afford convenient means for locking the slate trap in its high position at such times the jigger box is to be flushed.

35 Further purposes will appear in the specification and in the claims.

I have preferred to illustrate my invention by but one main type with a slight 40 variation in form, selecting a type which is practical, reliable and in a broad sense inexpensive and which at the same time well illustrates the principles of my invention.

45 Figure 1 is a vertical section through a jig and its conveyers.

Figure 2 is a detail section on line 2—2 of Figure 1.

50 Figure 3 is a view similar to Figure 1 with a modification as to the method of driving the slate conveyer.

Figure 4 is a section on line 4—4 of Figure 3 to illustrate a magnetic clutch drive for the slate conveyer.

Figure 5 is a detail vertical section of a modification showing a different method by 55 which the depth of slate in the jigger box may be made to control the operation of the slate conveyer.

In the operation of coal jigs corresponding to my Patents #1,225,157, #1,225,158 60 and #1,225,159, there has been a tendency for the slate to carry with it some coal by reason of the operation of the slate conveyer at times of insufficient depth of slate in the jigger box, resulting in a loss of coal unless 65 re-picking or re-jigging is resorted to.

In all the figures the same numbers of reference indicate like parts.

Describing the invention shown by way of illustration and not of limitation, I use 70 a tank 10 and plunger 11 with a perforated box bottom 12 within which I show a vertically movable perforated trap section 13, preferably perforated both at its bottom 13 and at its top 14.

75 This vertically movable trap is counter-weighted to depress according to the total weight of slate and coal in it and above it and as variation in this total weight is substantially a function of the quantity of slate present the vertically movable trap is depressed according to the depth of slate in the jigger box.

In connection with this trap, I illustrate 80 a gate 15 which keeps closed in the higher 85 positions of the trap, that is, closed when there is a relatively small depth of slate in the jigger box.

85 As slate accumulates above the trap, the trap automatically sinks by reason of the 90 increase in weight and the gate opens by reason of being too short to sink with the bottom of the trap upon which it rests in the higher positions of the trap.

When the gate is open, the trap is always 95 depressed by reason of the presence of a very considerable quantity of slate and admission into the trap is at this time sufficiently throttled to prevent any rush of slate into it.

100 The gate 15 is open only when the trap is near its lowest position which is only when there is an ample depth of slate above it.

105 When the trap rises, its bottom comes into contact with the lower edge of the gate, causing the gate to rise with it and the gate re-

mains closed, rising and falling with the trap except when the trap is below a predetermined depth.

When the trap sinks below this predetermined depth it sinks away from the lower edge of the gate leaving an opening for discharge of slate.

Experience has shown that if the slate conveyer 16 is in operation during the higher positions of the trap there may be some coal carried into the trap along with the slate, and to prevent this loss of coal the slate conveyer is only in operation when the trap is in its low position.

13 The movable slate trap is supported as explained in my inventions previously referred to by links to variable moment counterweighted levers which take care of the additional weight due to the accumulation of slate by an effective increase of arm when the trap sinks, the arrangement being one in which the trap will sink by reason of greater weight from accumulating slate to an extent that is exactly balanced by the greater moment of the counterweighted levers.

As explained in my patents above referred to, material oscillation of the trap with the oscillation of the water is prevented by means of a suitable damper 18.

36 The electrical switch 19 controls the operation of the slate conveyer and when this switch is open the slate conveyer does not operate.

This switch is open whenever the trap is 25 in the relatively higher positions and as the trap sinks into a relatively low position a projecting arm 20 on a fixed part of the supporting links 21, engages a pin 22 on a lever 23, resulting in closing switch 19, which 40 starts the slate conveyer, either by starting a motor 25 as shown in Figures 1 and 2, there being another motor 26 for operation of the coal conveyer or by closing a magnetic clutch 27 (Figures 3 and 4), on the shaft 28 of the 45 slate conveyer and a corresponding shaft 29 co-axial with 28 operated by chain drive 30 from the motor of the coal conveyer, see Figure 4.

Closing the switch 19 by reason of the low 50 position of the trap thus results in starting a motor 25 that is special to the slate conveyer or in closing a magnetic clutch 27 between the shaft of the slate conveyer and another shaft having continuous operation 55 from the motor of the coal conveyer.

Figure 5 shows a modification whereby the result of having the slate conveyer only operate when there is an ample depth of slate in the jigger box is accomplished differently.

60 A jiggling ball 31 with an arm 32 pivoted at 33 is made of such relative weight and volume that it occupies a position between the coal and slate in the jigger box, on top of the slate and beneath the coal, with the result 65 that it rises and falls with the depth of slate

in the jigger box, and the outer end of the arm 32 is made to engage the pin 22 of the switch operating lever 23 thereby controlling as in Figure 1 the operation of the slate conveyer, the arrangement as before being one in which a sufficient depth of slate results in closing a circuit that starts the slate conveyer to continuous operation until the depth of slate becomes insufficient when the circuit opens and the conveyer stops.

In operation there is a relatively small rise and fall of the slate trap 13.

As the slate accumulates above the trap, the trap is depressed by reason of the greater weight upon it and in it until the gate 15 begins to open and finally until the switch 19 is closed either by an arm 20 on some part of the supporting linkage or by means of the jiggling float 31.

The greater portion of the slate within the trap is now discharged through the gate 15 and the resultant lightening of the weight upon the trap causes it to rise which stops the slate conveyer by opening the switch 19 and closes the gate 15 by coming into contact at the projecting lip 41 with the lower edge of 15.

The area of admission into the trap 13 increases as the trap rises and the trap gradually becomes charged with slate with the result that as slate further accumulates above it, the trap again sinks and the whole operation is repeated.

It is desirable to be able to temporarily lock the trap 13, as for example preparatory to slushing the jigger box.

This is accomplished by means of a rod 34 attached to the bottom of the trap 13, passing through a stuffing box 35 and carried by a lever 36 hung by a link 37 to a fixture 38 on the bottom of the jigger box.

The lever 36 with pin hole 42 slides along a holed plate 39 and is set in any position with respect to 39 by means of a pin adapted to fix the lever at any desired position on 39.

The handle of this lever is conveniently placed along side of the handle of the slush gate 40 so that an operator, preparatory to slushing the jigger box, is enabled to lock the trap 13 into this higher position by moving the lever 36 upward and fixing it in place with a pin.

It will be evident that the weight does not increase above the movable section as rapidly as the weight of the slate in the movable section is reduced by discharge of the slate, both because there is not the same depth of addition within the same time and because the addition is not wholly slate.

I am aware that in view of my invention and disclosure modifications and variations of my invention to meet individual whim or particular need may become evident to others skilled in the art and I claim all such variations and modifications in so far as they

fall within the reasonable spirit and scope of my invention.

Having thus described my invention what I claim as new and desire to secure by Letters Patent is:—

1. In apparatus for separating slate and coal, a jigger box, a slate trap in the jigger box, means for automatic variation of the vertical position of the trap with the depth of slate in the jigger box, a slate conveyer and an automatic control between the vertical position of the trap and the operation of the conveyer.
- 10 2. In apparatus for separating slate and coal, a jigger box, a slate trap in the jigger box, means for automatic variation of the vertical position of the trap with the depth of slate in the jigger box comprising supporting linkage connected to the trap and a variable moment counterweight support connected to the linkage, a slate conveyer and an automatic control between the vertical position of the trap and the operation of the conveyer.
- 15 3. In an apparatus for separating coal and slate, a jigger box, a slate trap in the jigger box, means for automatic variation of the vertical position of the trap with the depth of slate in the jigger box connected to the trap and a variable moment counterweight support connected to the linkage, a slate conveyer and an automatic control between the vertical position of the trap and the operation of the conveyer.
- 20 4. In an apparatus for separating coal and slate, a jigger box, a slate trap in the jigger box, means for automatic variation of the vertical position of the trap with the depth of slate in the jigger box, a slate conveyer and an automatic control between the vertical position of the trap and the operation of the conveyer comprising a motor for the conveyer, an electric circuit controlling the drive of the conveyer by the motor, a switch in the circuit and mechanical linkage controlling the switch and operated by the trap.
- 25 5. In an apparatus for separating coal and slate, a jigger box, a slate trap in the jigger box, means for automatic variation of the vertical position of the trap with the depth of slate in the jigger box, a slate conveyer and an automatic control between the vertical position of the trap and the operation of the conveyer comprising a motor for the conveyer, an electric circuit controlling the drive of the conveyer by the motor, a switch in the circuit and mechanical linkage operated by the trap and controlling the switch, the motor being a magnetic clutch between a moving shaft and a shaft of the conveyer.

depth of slate in the jigger box, a slate conveyer and an automatic control between the vertical position of the trap and the operation of the conveyer comprising a motor for the conveyer, an electric circuit controlling the drive of the conveyer by the motor, a switch in the circuit and mechanical linkage controlling the switch and operated by the trap.

4. In an apparatus for separating coal and slate, a jigger box, a slate trap in the jigger box, means for automatic variation of the vertical position of the trap with the depth of slate in the jigger box, a slate conveyer and an automatic control between the vertical position of the trap and the operation of the conveyer comprising a motor for the conveyer, an electric circuit controlling the drive of the conveyer by the motor, a switch in the circuit and mechanical linkage operated by the trap and controlling the switch, the motor being a magnetic clutch between a moving shaft and a shaft of the conveyer.

Signed at Chicago, county of Cook and State of Illinois, this 7th day of October, 1922.

HARRY J. MOYER.
